CLAIM

We claim the ornamental design for a nested tableware set, as shown and described.

DESCRIPTION

FIG. 1 is a top perspective view of a nested tableware set, showing a first embodiment of our new design;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top plan view thereof;
FIG. 7 is a bottom plan view thereof; and,
FIG. 8 is an exploded view thereof, showing the bowls and plates that are nested to form the nested tableware set.
The broken lines shown in FIG. 8 show portions of the nested tableware set that form no part of the claimed design.
